[57] CLAIM

The ornamental design for a portable table, as shown and described.

DESCRIPTION

FIG. 1 is a top right front perspective view of a portable table showing our new design;

FIG. 2 is a front elevational view thereof;

FIG. 3 is a top plan view thereof;

FIG. 4 is a right side elevational view thereof;

FIG. 5 is a left side elevational view thereof; and,

FIG. 6 is a rear elevational view thereof.

The broken lines are for illustrative purposes only and form no part of the claimed design.
